(57) **CLAIM**

The ornamental design for a camera filter, as shown and described.

DESCRIPTION

FIG. 1 is a front, bottom and left side perspective view of a camera filter showing our new design;

FIG. 2 is a front, top and right side perspective view thereof;

FIG. 3 is a rear, top and left side perspective view thereof;

FIG. 4 is a rear, bottom and right side perspective view thereof;

FIG. 5 is a front elevational view thereof;

FIG. 6 is a rear elevational view thereof;

FIG. 7 is a bottom plan view thereof;

FIG. 8 is a top plan view thereof;

FIG. 9 is a right side elevational view thereof; and,

FIG. 10 is a left side elevational view thereof.

The broken lines depict portions of a camera filter in which the design is embodied and form no part of the claimed design.

The “GoPro” mark shown in FIGS. 2, 4, and 9 is a registered trademark of GoPro Inc. The “GoPro” mark forms no part of the claimed design.
